WIRE FENCE GATE

Ernest Wilson, Los Angeles, Calif.

Application August 31, 1949, Serial No. 113,336

1 Claim. (Cl. 256—2)

1
This invention appertains to a gate for wire fences, especially barbed wire fences, and has for an object to provide a simple, convenient, and effective means to be applied to adjacent strands of a wire fence to spread the same apart to permit of the easy passage of an individual through the opening so formed, with a minimum of danger of injury to the person or his or her clothing.

Another object of the invention has to do with the provision of a means of the above mentioned character and which is collapsible for its easy and convenient portage from one point of use to another, thus making it possible to take short cuts across wire fenced fields to save time and energy that would otherwise be expended in seeking out and manipulating the gates ordinarily provided for entry and exit.

Still another object of the invention is to provide a handy carrier for the gate parts when the same are collapsed and nested together and from which the parts may be quickly extracted and likewise installed.

With these and other objects and advantages in view, the invention resides in the certain new and useful combination, construction, and arrangement of parts, as will be hereinafter more fully described, set forth in the appended claim, and illustrated in the accompanying drawings, wherein:

Figure 1 is a perspective view of a section of a barbed wire fence and showing the gate structure applied thereto, the gate also being in perspective;

Figure 2 is an enlarged fragmentary perspective view of the lower end portion of one of the extensible wire spreading members and showing the cooperative relation of the pawl and rack for permitting the adjustment of the relatively movable parts of the member and to hold the parts fixed in the adjusted positions thereof;

Figure 3 is a vertical section taken through the line 3—3 on Figure 2, looking in the direction of the arrows; and,

Figure 4 is a side view of a carrier for the gate structure, when it is collapsed and nested within the carrier for portage.

Referring to the drawings, and more particularly to Figure 1, P designates a pair of fence posts supporting three strands of barbed wire, designated from top to bottom at a, b, and c, respectively.

Generally, the invention is comprised in a pair of identical extensible, or jack-knife, members adapted to be engaged, in spaced apart relation,

2
between adjacent strands of the barbed wire, preferably, strands b and c, extending between the post P; means to allow for the extended and collapsed adjustment of the relatively movable parts of each member and to hold the same at the positions of adjustment; and a flexible element interconnecting the upper ends of the members to protect the person and his or her clothing against contact with the upper of the wires.

As shown, each of the extensible members is comprised in a pair of elongated metal bars 10 and 12, rectangular in cross-section, disposed in parallel relation for relative endwise movements of adjustment into either extended or collapsed state, the lower and upper ends of the bars 10 and 12 being V-notched, as at 14, for the engagement of the same with the wire strands c and b, respectively. The upper end of the bar 10 is provided with a laterally offset plate 16, which is apertured for the sliding engagement of the upper end of the bar 12 therewith, while the lower end of the bar 10 is likewise provided with a laterally offset plate 18, secured thereto, as by a pin 10a or in any other suitable manner, for the sliding engagement of the lower end of the bar 12 therewith; the two plates extending from the bar ends in right angular relation with respect thereto.

The bar 12 has its outer side face formed to provide a series of rack teeth 20 intermediate its ends and a pawl 22 is mounted on the plate 18 for cooperation therewith; the pawl preferably being made of a length of flat spring steel which has its lower end outwardly bent at an obtuse angle to provide a foot portion 24, secured to the plate 18, outwardly from the opening through which the bar 12 depends, and its upper end outwardly bent at an acute angle to provide a rack tooth engaging portion 26. Engaged within the angle of the portion 26, of the pawl 22, is the substantially straight end portion 28 of an operating element which is also made of a length of flat spring steel and has its lower end portion 30 extending downwardly through a second opening formed in the plate 18, outwardly from the foot portion 24, of the pawl 22, and curving inwardly toward the lower end of the bar 12 to provide a finger-piece for actuating the element to affect the release of the pawl from the rack. A pair of ears 32 is formed on the opposite side edges of the operating element, at the point of its passage through the opening, and these are engaged on a pivot pin 34 which is inserted inwardly of a transverse bore opening

through a side edge of the plate 18 and extends across the opening for the purpose.

With the extensible members interposed between the wire strands *b* and *c* and adjusted to spread the same apart, as shown in Figure 1, and in order to protect the person or his or her clothing from otherwise possible injury or damage in passing through the gap beneath the upper wire strand *b*, a strip of a flexible material, such as heavy weight canvas or the like, indicated at 36, is stretched between the extensible members and detachably fastened, as at 38, to the plates 16.

To have the gate, as thus constituted, available for use at all times, particularly by farmers and others having need to traverse areas fenced in with barbed wire, a carrier 40 is provided for its portage from one point of desired entry or exit through a fence to another, and the same is comprised in an elongated bag, of canvas or other suitable material, having a flap closure 42 and a hand grip 46 at its open end, the flap being secured in closed state by suitable means, such as a snap fastener 44.

In use, the extensible members are adjusted to their shortest length and nested together, along with the protector strip 36 in folded state, for insertion inwardly of the mouth of the bag 40; the adjustment of the individual members being affected by finger pressure exerted against the outer side of the lower curved portion of the operator 28 which tensions the upper end portion thereof sufficiently for it to snap the pawl 22 free from engagement with a tooth of the rack 20, when the bars 10 and 12 may be shifted endwise as required.

Having thus fully described my invention, it is

to be understood that the words which I have used are words of description rather than of limitation, and that changes within the purview of the appended claim may be made without departing from the true scope and spirit of the invention in its broader aspects.

What I claim is:

A gate for providing a passageway through a barbed wire fence, comprising in combination a pair of identical adjustably extensible members 10 adapted to be interposed vertically in spaced apart relation between adjacent strands of wire to spread the same apart, each of said members being comprised in a pair of parallel bars, means at the inner ends of said bars interconnecting the same for relative movements of adjustment, means at the outer ends of said bars for engagement with the adjacent strands of wire, cooperative means carried by said bars to secure the same in adjusted state, and a protector strip of flexible material stretched between the upper ends of said members to lie below the upper one of the wire strands to prevent contact of the person passing through the opening between the spread wires with the upper one thereof.

ERNEST WILSON.
